FIG. 19

PLASTICS CONTAINERS

This invention relates to containers made from thermoplastics material, hereinafter called plastics containers.

More particularly the invention relates to open-topped thin-walled disposable plastics containers. Such containers may be in the form of cups for solids or liquids, e.g. beverages, or tubs for ice cream. By "thin-walled" plastics containers is meant containers through the sidewall of which heat is conducted to or from the contents of the container at a rate which makes the container when charged with contents uncomfortable to handle. It is, of course, most desirable that such containers should be insulated to avoid discomfort to the user of the container. In the past it has been proposed to make a thin-walled plastics container comprising an inner member having a bottom wall and a sidewall extending from the bottom wall to the open top rim of the container and a second member within which the first member is disposed and having bottom and sidewalls closely spaced from the corresponding walls of the first member, the first and second members being connected together by a seam at the top rim of the container. The formation of this known insulating container is wasteful of plastics material and involves the separate formation of the inner and outer members followed by the seaming together thereof.

It is an object of the present invention to form an open-topped, thin-walled disposable plastics container which is economical in the use of plastics material and does not involve the separate formation and subsequent seaming together of the inner and outer members.

The present invention consists in an open-topped, thin-walled disposable plastics container formed from thermoplastic sheet material, comprising an inner member having a bottom wall and a sidewall which extends from the bottom wall to the top rim of the container and an outer, heat-insulating member comprising a skirt which depends from the top rim of the container closely alongside the sidewall of the inner member and is formed in one with the inner member and from one end the same piece of thermoplastic sheet material from which the inner member is formed.

Suitably, the outer heat-insulating member depends from the container rim to a level intermediate the rim and the bottom wall of the inner member.

Advantageously, the inner member of the container is formed on the container rim side of the level to which the outer member depends with an inwardly extending shoulder whereby the container is stackable with like containers by reason of the edge of the outer member of the container remote from the rim of the container engaging the inwardly projecting shoulder of the container therebelow thereby to space the inner member of one container from the inner member of the container therebelow.

In one form of the invention the outer member of the container is formed with an outwardly projecting portion serving in use as a handle for the container.

The invention also consists in the method of forming a thin-walled, open-topped disposable heat-insulated plastics container which includes clamping around an open end of a female tool member a sheet of heated plastics material, drawing the sheet in a direction away from the female tool member thereby utilizing a peripheral part of the sheet to form an outer member of the container open at its end adjacent the female tool member, moving a central part of the sheet in a direction towards the female tool member through the formed outer member, forming the part of the sheet within the formed outer member into an inner container member relative to which the outer member constitutes an insulating skirt depending from the rim of the inner container member in close proximity to part of the inner container member extending from the rim thereof, and, severing the formed container from the plastics sheet.

The invention further consists in tooling apparatus for forming an open-topped thin-walled, disposable plastics container from thermoplastic sheet material comprising a base member formed with a bore and a female tool member slidably fitted

within the bore, a clamp for clamping sheet plastics material around an open end of the female tool member, means for projecting the female tool member from and retracting the female tool member into the base member, the projection of the female tool member serving to stretch the sheet plastics material between the frame clamp and the female tool member, a reciprocable knife member movable to engage the sheet material between the clamp and the female tool member having an inner surface which when the knife member is engaged with the sheet material defines the outer member of the container to be formed, means for transferring sheet material between the clamp and the female tool member to the inner surface of the knife assembly to define the outer container member, a reciprocable head member movable to engage the end of the knife member remote from the end thereof which engages the sheet material between the clamp and the female tool member, an assist plug mounted in the head member and reciprocably movable so that with the head member engaged with the knife member and the latter member engaged around the female tool member between the clamp and the female tool member and the sheet material engaged with the inner surface of the knife member, the assist plug can be projected into the female tool member thereby to pass plastic sheet material through the knife member and into the female tool member for forming an inner member of the container.

The invention will now be described, by way of example, with reference to the accompanying drawings in which:

FIG. 1 is a side elevation to an enlarged scale of an open-topped, thin-walled, disposable plastics container for use as a stackable cup in a vending machine and formed from thermoplastic sheet material.

FIG. 1a is a fragmentary sectional view, at an enlarged scale, taken on the line 1a-1a of FIG. 1.

FIG. 2 is a sectional view showing a stack of containers of the kind shown in FIG. 1.

FIGS. 3 to 11 illustrate fragmentary sectional side elevations of tooling apparatus for the manufacture of containers in the form shown in FIGS. 1 and 2, the different views illustrating the location of parts of the tooling apparatus at different stages in the container forming operation.

FIG. 12 is a plan view of a base member of the tooling apparatus illustrated in FIGS. 3 to 11.

FIG. 13 is an underplan view of a head member of the tooling apparatus of FIGS. 3 to 11.

FIGS. 14 and 15 are respective underplan and topplan views of a knife assembly forming part of the tooling apparatus of FIGS. 3 to 11.

FIG. 16 is an under plan view of a frame clamp forming part of the tooling apparatus of FIGS. 3 to 11; and,

FIGS. 17, 18 and 19 illustrate other forms of container which can be produced on tooling apparatus similar to that in accordance with FIGS. 3 to 11 by the same technique as is hereinafter described for the production of containers according to FIG. 1.

Throughout the drawings like parts have been accorded the same references. It should be noted in the following description that the words "upper" and "lower" are used with reference to the cup rim being its upper end and the cup base its lower end. However, it should be understood that the orientation of the tooling may be such that the cup is not formed in a vertical position but in a horizontal position.

Referring first to FIG. 1 a thin-walled open-topped disposable plastics container is in the form of a stackable cup 1 for use in a vending machine. The cup comprises an inner member 3 having a bottom wall 5 and a sidewall 7 which extends from the bottom wall to the top rim 9 of the cup and an outer heat insulating member comprising a skirt 11 which depends from the top rim 9 of the cup closely along the side of an upper part of the sidewall 7 of the inner member 3 and is formed in one with the inner member 3 from one and the same piece of sheet plastics material, suitably, high-impact polystyrene, from which the inner member is formed.

The cup is formed so as to be stackable with similar cups so that when used in a vending machine cups are dispensed one at a time from the bottom of the stack. To this end the inner member 3 is formed in its sidewall 7 with a shoulder 13 located between the rim 9 and the edge 15 of the skirt 11 remote from the rim 9, the shoulder 13 being closer to the edge 15 than to the rim 9. Also, the skirt 11 is formed with longitudinally extending flutes or corrugations (not shown) of shallow depth, while the shoulder 13 is formed with radially extending flutes or corrugations (not shown) of shallow depth. Thus, when the cup 1 is stacked with similar cups the bottom and sidewalls 5 and 7 of the inner member 3 of one cup are spaced from the corresponding parts of the cup therebelow and the bottom edge 15 of the skirt 11 of one cup engages the shoulder 13 of the inner member 3 of the cup therebelow while the bottom of the rim 9 of one cup is spaced a short distance from the top of the rim 9 of the cup therebelow. The longitudinal flutes of the skirt 11 of an upper cup thus communicate at one end with the gap between the rims 9 of said upper cup and the cup immediately therebelow. These flutes at their lower ends communicate with the radial flutes in the shoulder 13 of the lower cup. The longitudinal flutes in the skirt 11 of one cup together with the radial flutes in the shoulder 13 of the cup therebelow thus provide communication between atmosphere and the space between the bottom walls 5 and sidewalls 7 of successive cups in the stack. The tendency therefore for the weight of the stack to force out air in the interspace between cups is inhibited and in consequence the tendency in use of the stack in a vending machine to dispense the cups from the bottom of the stack more than one at a time is largely, if not wholly prevented.

It will be observed that the skirt 11 is closely spaced alongside the part of the inner wall 7 of the inner member 3, which extends from the rim 9. The narrow airspace formed between the skirt 11 and the part of the inner wall 7 alongside the skirt 11 affords heat insulation for hot or cold contents of the cup 1. The cup can thus be held by engagement of the user's hand with the skirt 11 without the contents of the cup causing discomfort.

The tooling apparatus for making the stackable vending cup 1 comprises a base assembly 21, a head assembly 23, a clamping frame 25 and a knife assembly 27.

The base assembly 21, details of which appear particularly in FIGS. 3 to 12, comprises a baseplate 29 formed with parallel ducts 31 and 33, the ducts 33 alternating with the ducts 31. The ducts 31 are for the conveyance of cooling fluid through the baseplate 29 whilst the ducts 33 are for the conveyance of air as hereinafter described. On the baseplate 29 is formed an array of hollow cylindrical bores 35, each having a lower part 37 of larger diameter than an upper part 39 thereof, the parts 37 and 39 of each bore 35 meeting at a radial shoulder 41. The bores 35 are formed by assembling and securing together a succession of plates 43, 45, 47, 49 and 51. The bores 35 are then formed by forming through the plates 43 to 51 bores of the diameter of the upper part 39 and subsequently counterboring the lower parts 37. Prior to assembly of the plates 43 to 51 the lower surface of the plate 45 is formed with radial grooves 53 which extend from a central deeper groove 55. Thus on assembly of the plates 43 and 45 the grooves 55 form a rectangular lattice of supply ducts through which air can be supplied to or withdrawn from the radial passages formed by the radial grooves 53 connecting the grooves 55 with the bores 35. Similarly, the upper surface of the plate 45 is formed with radial grooves 57 extending from a central groove 59. After assembly of the plates 45 and 47 the grooves 59 form with the lower surface of the plate 47 a rectangular lattice of ducts through which air can be supplied to or withdrawn from the radial passages defined by the grooves 57. A similar rectangular lattice of ducts 61 and radial passages 63 is formed between the plates 47 and 49 and between the plates 49 and 51 is similarly defined a rectangular lattice of ducts 65 and radial passages 67.

Slidably fitted in each cylindrical bore 35 is a female tool or cup cavity member 69 comprising a lower part 71 of a diameter such as to be a sliding fit in the lower part 37 of the bore 35 and an upper part 73 which extends from the part 71 and is a sliding fit in the upper part 39 of the bore 35. The shape of the upper surface of the part 71 and the shape of the inner surface of the part 73 of each cup cavity member 69 corresponds with the bottom wall 5 and lower part of the sidewall 7 of the inner member 3 of the finished cup 1. The inner surface of the part 73 thus tapers slightly downwardly.

The outer surface of the part 71 of each cup cavity member which engages the lower part 37 of the bore 35 is formed with upper, intermediate, and lower annular grooves 75, 77 and 79. In the retracted or lowermost position of the cup cavity member 69 the grooves 77 communicate the air passages 53 by way of passages 81 in the parts 71 with the interior of the cup cavity members 69.

In the projected or uppermost position of each cup cavity member 69 the annular groove 77 thereof communicates the interior of the cup cavity member by way of the passages 81 with the lattice of grooves 59 so that in the projected position of the cup cavity member 69 air can be supplied by way of the lattice of grooves 59 to or withdraw from the interior of the cup cavity member 69. The upper and lower annular grooves 75 and 79 accommodate sealing members (not shown) such as O-rings.

The overall length of the cup cavity member 69 is a little greater than the length of the bore 35 in the base assembly 21 so that in the retracted position of the cup cavity member 69 the latter projects a short distance above the upper surface of the plate 51, this plate 51 being hardened and forming an anvil plate for the knife edges of the knife assembly 27 hereinafter described. The upper end surface 83 of the cup cavity member 69 is formed with radially directed shallow flutes (not shown).

It should be noted that the clearance between the cup cavity members 69 and the anvil plate 51 is sufficient to permit passage of air from the lattice of ducts 65 and the passages 67 between the member 69 and the plate 51. Also, of course, if suction is applied to the ducts 65 air flows into the ducts 65 via the clearance between the anvil plate 51 and the member 69 and thence via the passages 67.

It will be appreciated that in order to project each cup cavity member 69 to its uppermost position, air pressure is supplied to the ducts 33 from which it passes through passages 85 to the underside of the part 71 of the cup cavity member 69. At the same time the ducts 59 and 61 are vented to atmosphere so that the differential pressure thus created across the part 71 effects upward movement of the member 69. Venting of the ducts 33 to atmosphere and the supply of air pressure to the ducts 61 and 59 causes retraction of the member 69 to its lowermost position.

Above the base assembly 21 is disposed a clamping frame 25 which serves to secure a heated plastics sheet 100 consisting of high-impact polystyrene from which cups are formed by the tooling apparatus relative to the upper surface of the anvil plate 51 and the upper end of each cup cavity member 69. The clamping frame 25, as seen more particularly in FIG. 16, consists of a plate 91 in which are formed circular apertures 93 which taper upwardly. At the lower side of each aperture 93 the diameter thereof is a maximum and equal to the diameter of each cup cavity member plus the minimum distance between the tops of adjacent members 69. The apertures 93 are coaxial with the bores 35.

Above the clamping frame 91 is disposed the knife assembly 27. The knife assembly consists of knives 101, supported on a frame formed by lower and upper plates 103 and 105. The plates 103 and 105 are formed with corresponding cylindrical apertures within which the knives 101 engage. The plate 103 on its upper surface is formed with grooves 107 which in the assembled position of the plates 103 and 105 form a rectangular lattice of ducts through which, in operation, cooling fluid is circulated rearwardly external

At the upper surface of the plate 105 are formed circular recesses 109 which cooperate with surfaces of the knives 101 to form interconnected circular ducts which communicate with the interior of the knife assembly through passages 111. Each knife is formed in a rectangular plate 113 secured to the plate 105. Centrally in the plate 113 is a circular downwardly tapering aperture, the rear edge 115 of which constitutes the cutting or knife edge of the knife assembly 27. Adjacent the knife edge 115 the aperture 113 is defined by a rearwardly tapering surface 117, against which surface the skirt 11 of the cup 1 is formed as hereinafter described. At the upper end of the surface 117 is an arcuate recess 119 into which open the passages 111. The recess 119 defines the lower part of the rim 9 of the cup 1. The plates 113 in their external configuration are rectangular at upper parts thereof and an intermediate external surface 121 of each plate 113 is cylindrical and fits closely within the cylindrical apertures defined by the plates 105 and 103. A lowermost part 123 of the external surface of each plate 113 is frustoconical and tapers downwards to the knife edge 115. The diameter of the knife edge 115 is slightly greater than the external diameter of the cup cavity member 69 therebelow. The internal surface 117 of the plates 113 is fluted with longitudinally extending shallow flutes so as to impart to the skirt 11 the fluted configuration required for the purposes mentioned above.

Above the knife assembly 27 is the head assembly 23. This comprises a block 125 formed with bores 127 which are coaxial with the respective bores 35. Secured to the lower face 126 of the block 125 are block elements 129 each having a flat upper surface 131 which engages the lower surface 126 of the block 125. The elements 129 have an overall section which is square so that the block elements fit accurately together and each block element is formed with a downwardly facing dome-shaped recess 133 at the top of which a central bore 135 of the block element 129 extends between the recess 133 and the bore 127. Slidably fitted within each bore 135 is an assist plug 137, the upper end of which is formed with an enlargement 139 which slidably engages the bore 127. At its upper end the block 129 fits to a head plate 141 formed with transverse passages 143 which communicate via short passages 145 with the bores 127. In the block 125 are formed upper transverse bores 147 through which, in operation, is circulated cooling fluid and lower transverse bores 149 into which open downwardly extending passages 151. The upper surface 131 of each block element 129 is formed with recesses 153 which open to the lower ends of the passages 155 and connect via further passages 157 with the dome-shaped recess 133. The lower face 126 of the block 125 is formed with grooves 159 from which lead short grooves 161 which communicate the grooves 159 with the bore 127. The engagement between the block elements 129 and the block 125 forms the grooves 159 into a rectangular lattice of ducts from which lead the short ducts formed by the grooves 161.

Each assist plug 137 is formed with an axial bore 163 which at its upper end and with the assist plug in its upper most position communicates via the short passage 145 with the transverse passage 143. In any position below its upper most position, the bore 163 of the assist plug communicates with the bore 127. At its lower end the bore 163 communicates via passages 165 with the dome-shaped recess 133.

At its lower outer edge the dome-shaped cavity 133 is formed with an annular spigot 167 which, during operation engages as a sliding fit in the upper end of the knife assembly 27, the lower surface of the spigot 167 is formed with a recess 169 which when the spigot is engaged in the knife assembly cooperates with the recess 119 of the knife assembly to define the rim 9 of the cup 1.

The method of forming the vending cup 1 can now be appreciated. At first, the base assembly 21, the clamping frame 25, the knife assembly 27 and the head assembly 23 are spaced apart in the relative positions indicated in FIG. 3 and the sheet 100 is disposed between the base assembly 21 and the clamping frame and knife assembly 25 and 27. By opera-

tion of mechanical or hydraulic means the head assembly 23 is caused to move towards the knife assembly 27 and also by a mechanical or hydraulic means the clamping frame 25 clamps the sheet 100 to the anvil plate 51 around each of the cavity cup members 69. This is the position reached in FIG. 4. The movement of the head assembly towards the knife assembly is continued and each cup cavity member 69 is projected upwards by the application of air pressure to the ducts 33 and the venting to atmosphere of the ducts 59 and 61. When the cup cavities 69 have been projected fully upwards, the position indicated in FIG. 5 is arrived at and the sheet 100 has been stretched particularly in the region between the clamping frame 25 and the upper end of each cup cavity 69. The motion of the head assembly downwards continues and movement of the knife assembly by mechanical or hydraulic means is initiated towards the cup cavity members 69. Suction is applied to the ducts 65 and because of the clearance between the anvil plate 51 and the cup cavity members 69 the space defined by the anvil plate 51, the cup cavity members 69 and the sheet 100 is evacuated and the sheet 100 is thus pulled into position alongside the external surface of the cup cavity member 69 and the surface of the anvil plate 51. This is the position indicated in FIG. 6.

The movement of the knife assembly 27 is continued until the knife assembly at its edge 115 engages, but does not penetrate, the sheet 100. Also, the head assembly 23 is further advanced until the spigot 167 begins to engage the upper end of the corresponding circular aperture therebelow in the knife assembly. The various parts of the tooling apparatus and the sheet 100 have now acquired the position indicated in FIG. 7. At this point the head assembly is retarded so that the final downward movement thereof to the position shown in FIG. 8 is gently accomplished. Suction is now applied to the bores 163 and the transverse bores 149 so that air is evacuated through the passages 157 and 165 to reduce pressure in each dome-shaped recess 133.

Suction is also applied to the ducts 109 and therefore in the passages 111 to evacuate the interior of the knife assembly adjacent each cup cavity member 69. Moreover, air pressure is supplied to the ducts 65 which passes by way of the passages 67 between the anvil plate 51 and each cup cavity member 69 and this air pressure forces the portion of the sheet 100 engaging the interior of each cup cavity member 69 outwardly to engage the fluted surface 117 of the knife assembly so as to define the skirt 11 of the cup. Air pressure is further applied to the ducts 59 and therefore by way of the passages 59 and 81 to the interior of the cup cavity. The effect of the application of suction and air pressure at the locations described is that the sheet 100 billows upwards and engages the sidewall of the dome-shaped cavity 133 and further engages in the recesses 119 and 169 in which the cup rim is formed. As previously explained, also, the skirt 11 is formed by the engagement of the sheet with the surface 113 of the knife assembly. As the transfer of the sheet from the cup cavity members 69 to the dome-shaped recesses 133 and the interior surfaces 117 of the knife assembly takes place, each cup cavity member is retracted by venting to atmosphere the associated duct 33 and applying air pressure to the ducts 59 and 61. The position now achieved is that shown in FIG. 8.

Air pressure is now applied to the transverse passages 143 and suction is applied to the ducts 159 with the result that each assist plug 137 is moved rapidly downwards. At the same time air pressure is applied to the transverse bores 149 with the result that air under pressure is admitted to the dome-shaped recess 133 by way of the passages 151 and 157. Suction is maintained in the passages 111 and is also now applied to the passages 81 by applying suction to the ducts 55. In the rapid downward movement of the assist plug 137 the plastic sheet 100 is first moved to the position shown by the broken lines 102. The pressure applied through the passages 157 and the suction applied at the passages 81 together with the suction maintained in the passages 111 causes movement of the sheet from the position shown by the broken lines 102 to the

position indicated in FIG. 9. It will be appreciated that in the movement of the sheet effected from the positions shown respectively in FIGS. 8 and 9, the interior member 3 of the cup is formed.

If desired, during the movement of the sheet which has been described to effect formation of the interior member 3 of the cup, suction can also be applied to the ducts 65 to assist in the formation of the shoulder 13 in the inner member 3 of the cup. However, this shoulder may be sufficiently well formed by simply venting to atmosphere the duct 65. The flutes (not shown) in the top surface of each cavity member 69 cause flutes to be formed in the shoulder 13 of the cup 1.

Each assist plug 137 is now retracted by being moved upwards, this movement being effected by applying suction to the transverse passages 143 and air under pressure to the ducts 159. Also, by mechanical or hydraulic means the force between the knife assembly 27 and the anvil plate 51 is increased to effect severance of the formed cups 1 from the sheet 100. Retraction of the head assembly 23 is then commenced by mechanical or hydraulic means. The position indicated in FIG. 10 is accordingly reached.

The retraction of the head assembly 23 is continued and the cup cavity members 69 are now advanced by the application of air pressure to the ducts 33 and the venting of ducts 59 and 61. The formed cups 1 are thus projected upwards relative to the remainder of the sheet which at this time still lies adjacent the anvil plate 51. Air pressure is now applied to the ducts 59 and from the ducts 59 to the passages 81 so that the cups 1 are blown out of the cup cavity 69. In practice, the sheet 100 is vertically disposed and the cups 1 are formed with their axes horizontal so that when the cups are blown out of the cup cavity 69 they fall in the space between the head assembly 23 of the knife assembly 27. The cups can of course be formed with their axes vertical in which event in addition to blowing the cups vertically out of the cup cavities 69 further air jets are provided to blow the cups laterally between the head and knife assemblies 23 and 27.

The cup cavities 69 are now once again retracted by applying suction to the ducts 33 and air pressure to the ducts 59 and 61 and the knife assembly and frame clamp 25 are moved mechanically or hydraulically to the positions thereof indicated in FIG. 3. The sheet 100 is then advanced to bring a fresh section thereof into position between the frame clamp 25 and the base assembly 21 whereupon a fresh cycle of operations is performed.

The cup formed by the vacuum forming process described is a thin-walled insulated disposable stackable cup, the thickness of the walls of the cup suitably being of the order of three to six thousandths of an inch. The cup is accordingly economical in its utilization of plastics material and this is, of course, particularly important as the cup is disposable. The inner and outer members of the cup container can be of cylindrical form or can taper towards or away from the bottom wall of the inner member of the cup container.

It will be clear that the outer member of the cup can be made to extend any desired fraction of the full depth or even beyond the full depth of the inner cup. Thus, in FIG. 17 there is illustrated a container in which the skirt 11 extends to a much greater depth than is the case with the skirt 11 of the container illustrated in FIG. 1.

In FIG. 18 there is illustrated a container formed by similar techniques to those described in the container illustrated in FIG. 1 in which the skirt 11 projects beyond the bottom wall 5 of the inner container 3. This form of container is very suitable as an ice cream or other food container.

In FIG. 19 there is illustrated a modified cup which can be made along the general lines of the technique described. However, it will be observed that this cup 200 has a projecting ear

201 which actually projects from the outer skirt 202 of the cup, the cup being insulated in its upper part by the skirt 202 and having a lower inwardly tapering part 203. In order to form the cup with the ear 201 the tooling assembly is modified 5 by providing in the base assembly an upwardly projectable plate which can be upwardly projected to a position in which it extends radially from the cup cavity 69 in the forward position thereof, in which position the sheet 100 is drawn down around the forwardly projected plate so as to form the projecting ear 10 201. The sides of the ear can be pinched together as at 204 to make the ear more effectively grippable.

I claim:

1. An open topped, thin-walled disposable plastic container formed from thermoplastic sheet material, comprising an inner body member having a sidewall that converges downwardly to the bottom of the container from a rim at its top and is formed with an inwardly extending shoulder between the rim and the bottom of the container, and an outer, heat-insulating member comprising a skirt which depends from said rim and embraces at least a substantial part of the inner member and extends convergently downwardly closely alongside the exterior of the latter and is formed in one therewith, said skirt being formed from one and the same piece of thermoplastic sheet material of which the body member is made, said inwardly extending shoulder being at a level between the rim and the lowermost edges of the skirt, and the outermost diameter of said skirt at said lowermost edge being less than the outermost diameter of said shoulder, whereby the container is stackable with like containers by reason of its skirt being engageable within the container therebelow, with the lowermost edge of the skirt engaging the inwardly projecting shoulder of said container therebelow, thereby to space the inner member of the container from the inner member of said container therebelow.
2. A container as claimed in claim 1, wherein the outer member and the shoulder of the inner member are so fluted that when the container is stacked with similar containers, passage means for air to the space between the inner member of successive containers in the stack is provided which leads 35 from between the rims of said successive containers, between the outer member of the upper and the inner member of the lower containers and thence between the shoulder of the lower container and the edge engaged therewith of the outer member of the upper container.
3. A container as claimed in claim 2, wherein the outer member is formed with longitudinally extending flutes and the shoulder of the inner member is formed with inwardly directed flutes, the flutes on the outer member providing, when the container is stacked with a similar container 40 therebelow, air passage means extending from between the rims of the container to the shoulder of the lower container whilst the flutes in the shoulder of the inner container extend said air passage means between the bottom of the outer member of the upper container and the shoulder of the lower container to the space between the inner members of the containers.
4. An open-topped, thin-walled, disposable plastic container formed from thermoplastic sheet material, comprising an inner body member having a sidewall that converges 45 downwardly to the bottom of the container from a rim at its top, and an outer, heating-insulating member comprising a skirt which depends from said rim to a level on the side of the bottom wall of the inner container remote from the container rim and extends convergently downwardly closely alongside the exterior of the latter and is formed in one therewith, said skirt being formed from one and the same piece of thermoplastic sheet material of which the body member is made.
